UNITED STATES PATENT OFFICE.

JOHN R. DAVIDSON AND BURTON C. KELLY, OF MONTICELLO, GEORGIA.

WAGON-HOUND.

No. 806,527.

Specification of Letters Patent.

Patented Dec. 5, 1905.

Application filed May 24, 1905. Serial No. 261,994.

To all whom it may concern:

Be it known that we, JOHN R. DAVIDSON and BURTON C. KELLY, citizens of the United States, and residents of Monticello, in the 5 county of Jasper and State of Georgia, have invented a new and Improved Wagon-Hound, of which the following is a full, clear, and exact description.

This invention relates to improvements in 10 the construction of hounds for wagons.

Hounds constructed wholly of wood, and because of the great scarcity of wood, are not only expensive when newly made, but the repairing of broken hounds is also somewhat 15 costly.

It is the object of our invention to provide a hound in which the wood portion consists of straight strips, which are not easily broken, as there are no cross-grain curves, and if 20 broken may be replaced at a comparatively small cost by either a wagon-maker or a person not skilled in the art.

We will describe a wagon-hound embodying 25 our invention and then point out the novel features in the appended claims.

Reference is to be had to the accompanying drawings, forming a part of this specification, in which similar characters of reference indicate corresponding parts in all the figures.

30 Figure 1 is a top plan of a hound construction embodying our invention. Fig. 2 is a side view thereof, partly in section. Fig. 3 is a bottom plan, and Fig. 4 is a section on the line $\alpha\alpha$ of Fig. 1.

35 Referring to the drawings, 1 designates divergent socket members consisting of metal, and in these socket members are wooden extension-pieces 2, secured, as here shown, by means of bolts 3, which pass through the 40 socket members and also through said extension. These bolts 3 further secure in place the forward ends of plates 4, the rear ends thereof being secured to the wooden extensions 2. These plates 4 are arranged above 45 the extensions 2, and underneath the same is a bed-bolster 5, and attached to the under side of the hound-sections is an axle 6. Bolted to the rear ends of the extensions 2 is the crossed bar or slide-bar 7.

50 The socket members 1 are preferably made in two sections, each section having inwardly-extended flanges 8 at the upper and lower sides, which form the upper and lower walls of a socket member to receive the tongue 9,

which is held in place by means of a bolt 10. 55 The rear end of the tongue 9 engages in the loop portion 11 of a metal strap 12, bolted to the hounds.

The castings or socket members are securely held in place by a top plate 13 and bottom 60 straps 14, bolts 15 passing through said top plate 13, through the side portions of the forward extensions of the socket members, and through said straps. From the rear bolts 15 brace-rod 16 extend rearwardly and outwardly 65 and have coiled ends 17 engaging around the axle. The extensions 2 of the hounds are further braced or connected to the socket members by plates 18, which are secured at the forward end to the socket members 70 passing underneath the axle 6 and bolted at the rear ends to the said extensions 2.

While the hound shown in the drawings is designed to be used at the front portion of a wagon, it is obvious that the rear hounds may 75 be substantially of the same form.

Having thus described our invention, we claim as new and desire to secure by Letters Patent—

1. A wagon-hound comprising rearwardly- 80 extending divergent socket members in separate pieces, upper and lower flanges extended forward from said socket members, a plate on the upper side of said forward extension, straps in the lower side thereof, and fastening- 85 bolts and wood extensions secured in the socket members.

2. A wagon-hound comprising rearwardly-extended socket members, the said socket members being divergent and in separate 90 pieces, upper and lower flanges extended forward from said socket members and forming the upper and lower walls of a socket member for receiving a tongue, a plate on the upper sides of said forward extensions, straps on 95 the lower side thereof, bolts passing through the plate, forward extensions and straps, and wood extensions secured in the divergent socket members.

In testimony whereof we have signed our 100 names to this specification in the presence of two subscribing witnesses.

JOHN R. DAVIDSON.
BURTON C. KELLY.
